UNITED STATES PATENT OFFICE.

THEODORE MULL, OF OLD FORT, OHIO.

GUIDE-BRACKET FOR EDGEWISE-MOVABLE DOORS.

No. 922,612.

Specification of Letters Patent.

Patented May 25, 1909.

Application filed April 27, 1907. Serial No. 370,686.

To all whom it may concern:

Be it known that I, THEODORE MULL, a citizen of the United States, residing at Old Fort, in the county of Seneca and State of Ohio, have invented certain new and useful Improvements in Guide-Brackets for Edge-wise-Movable Doors, of which the following is a specification, reference being had to the accompanying drawings.

10 My invention relates to improvements in railway cars and an object of my invention is to provide a railway car with a door which may be opened and closed easily and with adjustable devices which will permit the obtaining of a maximum ease of operation of the door.

In the drawings illustrating the principle of my invention and the best mode now known to me of applying that principle, 20 Figure 1 is an elevation of so much of a railway car as is necessary to illustrate my invention; Fig. 2 is a section on line A—A of Fig. 1; Fig. 3 is a sectional detail on line B—B of Fig. 1; Fig. 4 is a sectional detail on line C—C of Fig. 1; and Fig. 5 is a detail of the adjustable guide-bar for the lower portion of the door.

a is the side of the railway car to which is secured the blocks b each of which supports 30 an end of the track c. Upon the latter rest the balls d carried in the upper portion of a hanger f the lower portion of which is secured to the door g. When the door is moved relatively to the side of the car, each ball d is 35 moved against one of the walls of its corresponding recess and then slides along on the upper edge of the track c. To the lower edge of the door g is secured a pair of guide-plates h which are bent laterally under the 40 lower edge of the door g and then down-

wardly to form a projecting flange i, as is best shown in Fig. 4. To the side of the car is secured a guide-bar j by means of staples k which pass through holes m in the guide-bar j; and by bolts n which pass through elongated vertical slots o and upon the end of each of which is screwed a nut p. When it is desired to adjust the guide-bar j with reference to the flanges i, the nuts p are turned, whereupon the guide-bar j will rotate about its lower edge as is shown by dotted lines in Fig. 5. This adjustment of the guide-bar j permits one to attain ease of movement of the door under the varying conditions of service.

I claim:

1. The combination with a car, of a guide-bar secured thereto, said guide-bar being mounted free to be tilted; a door movably mounted upon said car; and guide-plates secured to said door, said guide-plates being formed with flanges which extend between said guide-bar and car.

2. The combination with a car, of a guide-bar mounted thereon free to be tilted and formed with holes; retaining devices which pass through said holes and control the tilting of said guide-bar; and a door provided with guiding devices which project between said guide-bar and said car.

In testimony whereof I have hereunto set my hand at said Tiffin, in said county and State this nineteenth day of April, A. D., 1907, in the presence of the two undersigned witnesses.

THEO. MULL.
